UNITED STATES PATENT OFFICE.

JOSEPH A. SEKORA, OF ANN ARBOR, MICHIGAN.

DESIGN FOR A CARRIAGE-POLE TIP.

SPECIFICATION forming part of Design No. 33,091, dated August 14, 1900.

Application filed April 16, 1900. Serial No. 13,143. Term of patent 14 years.

To all whom it may concern:

Be it known that I, JOSEPH A. SEKORA, a citizen of the United States, residing at Ann Arbor, in the county of Washtenaw, in the 5 State of Michigan, have invented and produced a new and original Design for a Carriage-Pole Tip, of which the following is a specification, reference being had to the accompanying drawings, forming part thereof.

10 This attachment is to be affixed to the under side of the carriage-pole near its forward end.

Figure 1 is a perspective. Fig. 2 is a side elevation. Fig. 3 is a front elevation.

15 The leading feature of the design consists in a forked bearing from which a stem extends downward and curves in a direction at right angles to the line connecting the two ends of the fork.

The two branches A and B of the fork are

united by a curved face *a* on the one side and 20 on the other side by curved faces *b* and *c* of a different radius than the inner face. The two faces *b* and *c* extend to a downturned stem *C*, that bends backward abruptly at *d* and is continued in a stem *D*, provided at its terminal 25 with holes *e*.

What I claim as new, and desire to secure, is—

30 The design for a carriage-pole tip, herein shown and described.

In testimony whereof I have signed my name to this specification in the presence of two subscribing witnesses.

JOSEPH A. SEKORA.
